UNITED STATES PATENT OFFICE.

LOUIS V. ARONSON, OF NEWARK, NEW JERSEY.

DESIGN FOR A COMBINED CIGAR-LIGHTER AND INKSTAND.

56,093.

Specification for Design.

Patented Aug. 17, 1920.

Application filed October 15, 1919. Serial No. 330,924. Term of patent 7 years.

To all whom it may concern:

Be it known that I, LOUIS V. ARONSON, a citizen of the United States, residing at Newark, in the county of Essex and State of New Jersey, have invented a new, original, and ornamental Design for a Combined Cigar-Lighter and Inkstand, of which the following is a specification, reference being had to the accompanying drawing, forming part thereof.

The figure is a plan view of a combined cigar lighter and inkstand, showing my new design.

I claim:

The ornamental design for a combined cigar lighter and inkstand, as shown.

LOUIS V. ARONSON.
